US00D993977S

(12) **United States Design Patent** (10) **Patent No.:** **US D993,977 S**
(45) **Date of Patent:** **** Aug. 1, 2023**

(54) **DISPLAY SCREEN OR PORTION THEREOF WITH GRAPHICAL USER INTERFACE**

(71) Applicant: **Lutron Technology Company LLC**,
Coopersburg, PA (US)

(72) Inventors: **Gregory Altonen**, Easton, PA (US);
Karelys Alfonzo, Coopersburg, PA (US); **Nayda Aponte**, Northampton, PA (US); **Shenchi Tian**, Easton, PA (US); **Brad Michael Kreschollek**, Bethlehem, PA (US)

(73) Assignee: **Lutron Technology Company LLC**,
Coopersburg, PA (US)

(**) Term: **15 Years**

(21) Appl. No.: **29/853,071**

(22) Filed: **Sep. 13, 2022**

Related U.S. Application Data

(63) Continuation of application No. 29/827,806, filed on Feb. 22, 2022, now Pat. No. Des. 966,322, which is a continuation of application No. 29/734,683, filed on May 14, 2020, now Pat. No. Des. 944,829.

CLAIM

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

The sole FIGURE is a front view of a display screen or portion thereof with graphical user interface showing the claimed design.

The peripheral dashed broken lines illustrate a display screen or portion thereof, and form no part of the claimed design. The interior broken lines illustrate portions of the graphical user interface which form no part of the claimed design.

1 Claim, 1 Drawing Sheet
(1 of 1 Drawing Sheet(s) Filed in Color)
